UNITED STATES PATENT OFFICE.

JOHN WILLIAM TULLY, OF KANSAS CITY, MISSOURI.

CASE FOR TOOTH-BRUSHES.

SPECIFICATION forming part of Letters Patent No. 678,594, dated July 16, 1901.

Application filed February 27, 1901. Serial No. 49,092. (No model.)

To all whom it may concern:

Be it known that I, JOHN WILLIAM TULLY, a citizen of the United States, residing at 1410 Main street, Kansas City, in the county of Jackson and State of Missouri, have invented certain new and useful Improvements in Cases for Tooth-Brushes; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to improvements in cases for tooth-brush heads designed to inclose the bristles of the brush to preserve the same in a clean condition when carried in the pocket or otherwise.

20 In traveling it is very desirable that a tooth-brush be continually on the person, and it has been found very objectionable to insert the same in the pocket when in a wet condition, since the same is very likely to become 25 dirty from coming in contact with the dust, &c., in the pocket; and it is the primary object of the invention to overcome this objection.

The invention contemplates the provision 30 of a casing or box adapted to receive brushes of various sizes and so ventilated that a brush in wet condition when inserted therein will be sufficiently ventilated to quickly dry the same.

35 Improved details in the construction and arrangement of the several parts of the device will be apparent from the detailed description hereinafter and the appended claims when taken in connection with the 40 accompanying drawings, forming part hereof.

In the drawings an embodiment of the invention is illustrated, and when hereinafter referring to the same like reference characters will refer to corresponding parts in the 45 several views.

Figure 1 is a bottom plan view of the casing, a brush being shown in dotted lines. Fig. 2 is a transverse sectional view on the line $\alpha\alpha$ of Fig. 1, the same being inverted; 50 and Figs. 3 and 4 are respectively end elevations of the casing.

Referring more specifically to the drawings, A designates the body portion of the

casing, preferably of rectangular shape, corresponding in contour to the configuration of 55 the ordinary tooth-brush, and B is a cover pivoted to one side thereof, normally held shut by a hook member b, engaging a spring-catch b' , and the same may be sprung open after the catch is released by an elongated 60 flat spring b'' , engaging the rear edge thereof.

One end of the body A is cut away, as at a, and projecting from the end in alinement with the opening formed by the cut-away portion is a sheet-metal spring-clasp C, substantially U-shaped in cross-section and adapted 65 to grasp the handle of various sizes of brushes adjacent to its head. The purpose of providing this clasp is to hold the brush rigidly when within the casing to prevent rattling of 70 the same, and also in the event of the casing being dropped and the lid swung open to prevent the brush from escaping therefrom.

To afford a thorough circulation through the bristles in case the brush is inclosed in 75 the box in a wet condition, I provide the air-openings D D' in the respective ends of the body A, as seen in Figs. 3 and 4.

Slight changes in the precise arrangement 80 of the details may be made without departing from the spirit of the invention.

Having thus described the invention, what is claimed as new, and desired to be secured by Letters Patent, is—

1. A tooth-brush receptacle comprising a casing cut away at one end, and a spring-clasp projecting from the casing in alinement with the opening formed by the cut-away portion thereof, substantially as described. 85

2. A tooth-brush receptacle comprising a casing having a cut-away portion at one end adapted to receive the handle of the brush, a cover for the casing, and a sheet-metal spring-clasp secured to the casing and projecting therefrom in alinement with the cut-away portion thereof, and adapted to grasp the handle of the brush, substantially as and for the purpose described. 90

In testimony whereof I affix my signature in 95 presence of two witnesses.

JOHN WILLIAM TULLY.
